UNITED STATES PATENT OFFICE.

ALFRED R. WILSON, OF DETROIT, MICHIGAN, ASSIGNOR TO HUTCHINS CAR ROOFING COMPANY, OF DETROIT, MICHIGAN, A CORPORATION OF MICHIGAN.

CAR ROOF.

Application filed August 30, 1918. Serial No. 252,072.

To all whom it may concern:

Be it known that I, ALFRED R. WILSON, a citizen of the United States of America, residing at Detroit, in the county of Wayne 5 and State of Michigan, have invented certain new and useful Improvements in Car Roofs, of which the following is a specification, reference being had therein to the accompanying drawings.

10 The invention relates to car roofs of that type in which the carlines extend above the roofing sheets and form the supports and weather-proofing caps therefor. One of the objects of the invention is to obtain a construction in which the carline flange above the roofing sheets has an inwardly or downwardly extending portion terminating adjacent to the sheets to more completely prevent moisture from getting access to the 15 side edges of the sheets. A further object is to obtain a construction in which the carline has down-turned ends which extend over the down-turned flanges at the ends of the roofing sheets and provide clearance 20 thereof. Other objects of the invention reside in the novel arrangements and combinations of parts as more fully hereinafter set forth.

In the drawings:

30 Figure 1 is a top plan view of the car roof, with parts broken away;

Figure 2 is a cross section on the line 2—2 of Figure 1;

Figure 3 is a side elevation partly in section of a portion of the roof;

Figure 4 is a cross-section on the line 4—4 of Figure 1;

Figures 5 and 6 are respectively a sectional side elevation and a top plan view 40 of a modification;

Figure 7 is a cross section showing a modified construction of roofing sheets;

Figures 8, 9 and 10 are respectively a side elevation of, a top plan view of, and 45 a cross section through a car roof showing a modified bracket for securing the carline to the side plate;

Figure 11 is a perspective view of the modified bracket.

50 A are the carlines of T-section having the webs A' and the lateral flanges A² at the upper edges of the webs, these carlines being arched transversely of the car and having the down-turned end portions B 55 overlapping the sides of the car. C are the

relatively movable roofing sheets extending from eaves to eaves of the car roof and provided at their side edges with the upwardly-extending flanges C' arranged below the lateral flanges of the carlines and 60 at their ends with the downturned flanges C² overlapping the sides of the cars. The carlines A are secured to the side plates D and have the end portions of their webs A' 65 cut away at E adjacent to the inner sides of the side plates, the intermediate portions of the webs extending therebetween. Brackets F arranged in pairs and upon opposite sides of the webs A' are secured thereto by the rivets F' and are also secured to the inner sides of the side plates D by the bolts F².

The roofing sheets C are supported intermediate the eaves of the car roof by the purlins G which are formed in sections G' 70 extending between the webs A' of the carlines. The sections are supported by the plates H, which are secured to the carlines by the inverted U-clips H', and the nuts H² threadedly engaging the ends of the legs 75 of the clips, the bases of the clips passing approximately through the neutral axis of the carlines so that the latter are not materially weakened. The ends of the sections G' are preferably recessed at G² for the reception of the bases of the clips and have the bores G³ therethrough for the legs of the clips, the arrangement being such that lateral movement of the sections is prevented.

80 For the purpose of weather-proofing the car roof the lateral flanges A² of the carlines are curved downwardly and the upwardly-extending flanges C' of the roofing sheets terminate in the lateral portions C³ 85 in engagement with the lateral flanges A² of the carlines. The upwardly-extending flanges are spaced from the webs A' of the carlines so that the roofing sheets are free to move relatively to the carlines to a limited extent.

90 To more thoroughly weather-proof the roof, the lateral flanges A² of the carlines terminate in the inwardly or downwardly-extending portions A³, the lower edges of 95 which are near the roofing sheets. The roofing sheets also have the raised reinforcing corrugations G which extend longitudinally thereof and are located near the inwardly-extending portions A³ of the car- 100

105

110

lines, whereby any moisture blown transversely of the sheets will tend to be deflected from the space between the lower edges of the inwardly-extending portions and the 5 sheets.

The downturned ends B of the carlines have the portions B' of the inwardly-extending portions A³ cut away adjacent to the downturned flanges C² of the roofing 10 sheets to provide clearance therefor, the inwardly extending portions below the downturned flanges extending adjacent to the facing D' to act as spacers. The downturned ends of the carlines are secured to the side plates D by the bolts F². To 15 weather-proof the car intermediate the side edges of the downturned flanges C² the flashing plates H³ are provided between the roofing sheets and the siding and side plates. 20 I are running-board saddles, preferably formed of pressed sheet metal, and comprising the complementary sections I' and I² each of which have the lower foot flanges J resting upon the lateral flanges A² of the carlines and secured thereto, as by spot welding. 25 The edges of these foot flanges extend down the inwardly extending portions A³ of the carlines to embrace the latter, whereby a stronger construction is made possible. 30 The complementary portions I' and I² have at their ends the inwardly-extending embossed portions J', through which pass the rivets J², for securing the complementary portions to each other to make 35 a rigid construction. The complementary portions also have the laterally-extending flanges K at their upper edges upon which the running-boards L are mounted, suitable securing means such as the bolts L' being provided for securing the running- 40 boards to the saddles.

As shown in the modified construction in Figures 5 and 6, the purlin sections G' are secured to the webs A' of the carlines by 45 the brackets M to prevent any lateral movement of the purlins relative to the carlines. The brackets are located upon opposite sides of the sections and have the flanges M' adjacent thereto through which the bolts N pass and the flanges M² adjacent to the webs A' through which the bolts N' pass. The bolts N and N' secure the pairs of flanges upon 50 opposite sides of the purlin sections and carline webs respectively. This construction 55 besides preventing lateral movement of the purlins, also assists in supporting the purlins upon the carlines.

In the modified construction of roofing sheets, shown in Figure 7, the sheets C in 60 addition to having the upwardly-extending flanges C' and the lateral portions C³, which contact with the lateral flanges A² of the carlines, have the outwardly and upwardly inclined portions O connecting the flanges C' and the lateral portions C³. These out-

wardly and upwardly inclined portions O permit greater relative movement between the roofing sheets and carlines besides giving greater flexibility to the roofing sheet edges to retain the lateral portion C³ of 70 the sheets in engagement with the lateral flanges A² of the carlines.

In Figures 8, 9, 10 and 11 the means for securing the web A' of the carline A to the side plate comprises the bracket P preferably formed of sheet metal and having the U-shaped portion P' for enclosing a portion of the web A' and also having the laterally-extending flanges P² lying adjacent to the side plate D and secured thereto by the 80 bolts F², which also secure the downturned end B of the carline. The U-shaped portion P' of the bracket has the apertures Q therein in registration with apertures R in the web A' through which suitable securing 85 means pass, such as the rivets S for rigidly securing the bracket to the carline.

What I claim as my invention, is:

1. In a car roof, the combination with a T-carline with its flange at the upper edge 90 of the web terminating in inwardly-extending portions, of roofing sheets weather-proofed by said carline and having downturned flanges at the eaves of the car roof, said carline flange also having downturned 95 portions at the eaves, the inwardly-extending portions of the flange being cut away adjacent to the downturned flanges of the sheets to provide clearance therefor and having their lower end below the ends of the sheets to provide spacing means.

2. In a car roof, the combination with the side plates at opposite sides of the car, of a T-carline extending thereacross and having its web extending between said side plates 105 and its flange downturned at the ends beyond said side plates, and means for securing said web and downturned flange portions to said side plates.

3. In a car roof, the combination with the 110 side plates at opposite sides of the car, of a T-carline extending thereacross and having its web extending between said side plates and its flange downturned at the ends 115 beyond said side plates, brackets upon the inner sides of said side plates and secured to said web, and a common means for securing said downturned flange portions and brackets to said side plates.

4. In a car roof, the combination with a 120 carline having a web and a laterally-extending flange, of a relatively-movable roofing sheet having a resilient upwardly-extending flange near said web, a lateral portion in sliding engagement with said carline flange, and an upwardly and outwardly inclined portion connecting said upwardly extending flange and lateral portion.

5. In a car roof, the combination with a 125 T-carline having a web, a substantially hori- 130

zontally extending flange at the upper edge of the web, and downwardly extending portions at the opposite edges of said flange, of relatively movable roofing sheets having upwardly extending flanges normally spaced from said web and terminating in substantially horizontal portions slidably engaging said flange, the contacting bearing surfaces

of said substantially horizontal flange and roofing sheet portions having relatively large areas, said downwardly-extending portions of said carline terminating near said roofing sheets. 10

In testimony whereof I affix my signature.

ALFRED R. WILSON.
